(57) CLAIM

I claim the ornamental design for a pump, as shown and described.

DESCRIPTION

FIG. 1 is a perspective view of an embodiment of a pump according to my new design;

FIG. 2 is a front view thereof;

FIG. 3 is a top view thereof;

FIG. 4 is a bottom view thereof;

FIG. 5 is a back view thereof;

FIG. 6 is a right side view thereof;

FIG. 7 is a left side view thereof; and,

FIG. 8 is a perspective view of an alternative embodiment of the pump according to my new design.
